APPETITE-INHIBITING COMPOSITIONS
 Larry Stein, Belmont Hills, Pa., assignor to American Home Products Corporation, New York, N.Y., a corporation of Delaware
 No Drawing. Filed Jan. 16, 1963, Ser. No. 251,746
 6 Claims. (Cl. 167—55)

This invention relates in general to compositions useful for appetite inhibition, and in particular to compositions which inhibit appetite while exhibiting greatly reduced side effects as compared with known appetite reducers.

It is now well recognized that weight control is most reliably effected by control of food intake, and recent years have seen a wide variety of approaches to the basic problem of reducing food intake.

One of the most appealing approaches has been the search for a compound in easily administered oral dosage form which would harmlessly reduce appetite to a level at which food intake was instinctively kept at the level commensurate with regulated weight loss or for maintenance of optimum weight. Amphetamine and various other phenethylamines such as mephentermine, methamphetamine, and phenmetrazine have been proposed for such a weight-control pill, and have been partially successful; however, these have had undesirable side effects, and their use has accordingly been limited to cases where these side effects could be ignored or tolerated. Specifically, amphetamine and the other phenethylamine-type compounds in appetite controlling dosages have been found to raise the blood pressure and to cause excitation. Also, these compounds have been found to have relatively short duration of activity.

As a most important facet of my discovery it has been found that the administration of this appetite suppressant composition not only results in the potentiation of the appetite-inhibiting effect of amphetamine, permitting the use of a much lower relative dosage of this component, but also blocks the peripheral pressor effect of amphetamine on the blood pressure. As a concrete illustration of this advantage may be noted the following test data on animals obtained experimentally: Femoral arterial blood pressure was recorded by means of a pressure transducer and electronic recorder in a series of anesthetized rats. In 4 rats, 0.5 mg./kg. of amphetamine administered intravenously increased blood pressure by 27/18 mm. mercury (systolic and diastolic readings). In a second group of 4 rats, the administration of 5 mg./kg. of one of my antidepressants (a polymethylene indole) by intravenous administration 30 minutes prior to like administration of amphetamine did not increase blood pressure of the animals, although in both cases appetite was depressed.

Therefore it is a prime object of the invention to provide a novel therapeutic composition capable of enhancing appetite suppression in mammals.

It is a second object of the invention to enhance said appetite suppression without a concurrent elevation in blood pressure of the animal so treated.

It has now been found, therefore, that quite unpredictably one may control appetite without such effects as mentioned by the use of an appetite reducing composition comprising essentially a phenethylamine as more particularly illustrated below, and, as a second principal ingredient, a member of a class of aminoalkyl polycyclic com-

2

pounds referred to in the field of pharmacology as "antidepressants." The term "antidepressant" as it has been employed herein serves to characterize these substances as a functional class. The functional activity of antidepressants has long been recognized as one of mood elevation or physiological energizing action when they are employed by themselves or in pharmaceutical preparations. It has been found that when admixed with a known appetite inhibitor such as various phenethylamines they promote the positive appetite suppressant effects and mute their negative pressor effects as demonstrated.

The phenethylamine component of my composition may be generally represented by the following generic formula:

20 and the pharmaceutically acceptable acid salts thereof, wherein Y equals

25 or

30 with Z representing hydrogen, or wherein Z and R₄ may be concatenated to form the general structure:

40 with n representing an integer from two to three; X represents a substituent such as hydrogen, halogen such as chlorine, bromine and the like, or trifluoromethyl; R₁ represents a lower alkyl group such as methyl or ethyl; R₂ represents either hydrogen or a methyl group; R₃ and R₄ each represent a substituent such as hydrogen or a lower alkyl group of up to about six carbon atoms such as methyl, ethyl, propyl, and the like.

45 With the employment of the dual-component therapeutic compositions of the above type, it is believed that the antidepressant substituted alkylamino component of the formulation generally depicted above exert some as yet not clearly understood effect on the appetite controlling center in the brain of mammals, causing them to react strongly to the phenethylamine component potentiated with such agents. However, it is not my intent to be bound by this mode of operation as other effects not presently recognized may in fact be involved in the action of the drug.

50 My invention recited therefore in its general product aspect involves the discovery that a combination of any of the known alkylamino substituted pharmaceutical compositions classed as "antidepressants" with a phenethylamine as illustrated above quite unexpectedly gives rise to a potent appetite suppressant agent substantially devoid of deleterious side effects. In a more limited product aspect my discovery involves the combination of a

particular antidepressant not heretofore known to the art, but disclosed in Rice et al. patent application Ser. No. 147,190, filed Oct. 24, 1961, now U.S. Patent No. 3,282,942, and Freed et al patent application Ser. No. 168,505, filed Jan. 24, 1962, now U.S. Patent No. 3,215,691, with the aforesaid phenethylamines to produce a like result.

The aforesaid novel antidepressant compounds disclosed in the copending patent applications referred to may be illustrated by the general formula:

II

and the pharmaceutically acceptable salts thereof wherein X is a member of the group consisting of hydrogen, halogen, lower alkyl, nitro, amino, hydroxy, and lower alkoxy; R and R' are hydrogen or lower alkyl; m is an integer of from zero to four; Am is a primary, secondary, or tertiary amine radical containing up to about eight carbon atoms, and D represents a bivalent organic radical selected from the group consisting of polymethylene radicals containing about 5 to 13 carbon atoms and aryl radicals of the formula:

The terms "lower alkyl" and "lower alkoxy" as employed in the above definition of my preferred antidepressant component includes both straight and branched chain alkyl radicals of less than about seven carbon atoms, such as methyl, propyl, etc. A particularly desirable and effective member of this class of antidepressants as defined hereinabove is a member wherein X represents hydrogen; R and R' represent hydrogen; Am represents dimethyl amino; and D is part of a cyclooctyl moiety, and m is 1.

As to the pharmaceutically acceptable salts of those antidepressant members which are novel, these may include acid addition salts of both inorganic acids, i.e., hydrochloric for example, or organic, i.e., acetic or propionic acids or compounds capable of forming such addition salts.

An appetite inhibiting composition containing the above cycloalkaneindole and a phenethylamine as generally described is especially found to be effective in that at doses of the order of 5 mg./kg. they more than double the anti-hunger action of d-amphetamine by positively potentiating its anti-hunger effect and negating its vasoconstrictor action. The utility of this combination in obese mammals suffering from high blood pressure but desirous of weight reduction is instantly obvious. The effect of the antidepressant component on the phenethylamine component may be summarized, to wit:

- (a) To augment and prolong the appetite inhibiting effect of the phenethylamine given, thus permitting a reduction in the dose of phenethylamine;
- (b) To increase the loss in weight produced by amphetamine;
- (c) To repress the vasoconstrictor activity of amphetamine.

The invention in its most general process aspect may be described as residing in the concept of reducing appetite in mammals by administration, preferably in oral dosage form, of the novel appetite suppressant composition herein broadly described. A preferred process aspect of the invention involves the concept of and actual administration to mammals, of a novel appetite suppressant composition comprising as active constituents the combination of 1 to 99 parts of a phenethylamine such as methamphetamine with an aminoalkyl polycyclic compound presently recognized to exhibit the property of reducing depression in animals making up the remainder of the active ingredients.

In one of its most preferred process aspects the invention involves the concept and specific administration of 15 a member of the particular class of N-(aminoalkyl) indoles or its pharmaceutically acceptable salts as described above in combination with a phenethylamine to mammals to reduce appetite therein. When so administered the therapeutically effective quantity or unit dosage of the 20 appetite suppressant agent can vary over rather wide limits, depending upon the therapeutic effect desired. In general the daily dosages per kilo of body weight can vary from about 5 to 200 mg. of the composition. Each unit dosage form of the novel therapeutic composition can 25 contain from about 5 to 95 percent of active ingredients in the ratios above noted and preferably for most rapid result from about 50 to 95 percent of the novel therapeutic agents by weight of the entire composition with the remainder comprising various pharmaceutical carriers.

30 By the term pharmaceutical carriers I intend to include those non-therapeutic materials which are conventionally used in unit dosage forms, and thus include various fillers, diluents, binders, lubricants, disintegrating agents, and solvents. It is of course to be understood that the novel 35 composition may be administered without such carrier if desired, and may be administered either prior to or following the onset of the condition treated.

Various pharmacologic procedures were carried out 40 in test animals to evaluate the appetite inhibiting effect of these novel therapeutic agents. A convenient and effective means of demonstrating the effectiveness of the compositions is illustrated in the following specific embodiment of my invention which illustrates its preferred mode of use and the advantages attained as a result of the practice of such mode. It is of course to be understood that the following examples are purely for purposes of further illustrating the invention and may not be considered as definitive of its scope. For a proper legal 45 definition of what I consider my invention to be, attention may be directed solely to the several appended claims. 50 Unless otherwise indicated, quantities are in grams and parts are in parts by weight.

EXAMPLE 1

Food consumption test in rats

55 The test herein described measures behavior in rats. For this purpose, non-deprived rats are used; that is, a supply of regular laboratory chow is always available to the animals. During the test, sweetened condensed milk is also 60 made available to them from modified graduated pipettes; the volume of milk consumed in a given time interval indicates the effect, if any, the drug under study has on the appetite.

Sprague-Dawley strain laboratory white rats, aged 65 about six months and weighing from about 250 g. to 600 g., were maintained in individual cages with laboratory chow and water always available to them. During the test period each cage was also provided with a graduated milk dispenser containing sweetened condensed milk. For each 70 rat there was first determined the normal or "control" rate of milk consumption by observation at 15 minute intervals over a period of 120 minutes. On drug test days the rats were injected intraperitoneally with test compound, and after 20 minutes, 0.5 mg./kg. of d-amphetamine sulfate was injected intraperitoneally. Milk intake was then 75

observed after 15, 30, 60, and 120 minutes. The results are summarized in the following table:

Drug and Dosage	No. of Rats	Average Milk Intake (percent of no drug control)	
		15 min.	60 min.
A (5.0 mg./kg.)+C	30	28	73
B (5.0 mg./kg.)+C	5	37	83
C (0.5 mg./kg.)	30	63	91

A=1-(3-dimethylaminopropyl)-2,3-hexamethyleneindole hydrochloride.

B=11-(3-dimethylaminopropyl)-5,6-dihydro-11H-benz[a]carbazole hydrochloride.

C=Amphetamine sulfate.

EXAMPLE 2

In an experiment similar to that described in Example 1, the potentiation by N-(3-dimethylaminopropyl)-2,3-hexamethyleneindole of the appetite suppressing effects of various drugs was compared. The results are summarized in the following table:

Drug Treatment	No. of Rats	Milk Intake (percent of control)	
		After 15 min.	After 60 min.
Mephentermine sulfate, 2 mg./kg.	20	62	87
Mephentermine sulfate, 2 mg./kg. plus 5 mg./kg. of N-(3-dimethylaminopropyl)-2,3-hexamethyleneindole hydrochloride.	19	23	54
d-Amphetamine sulfate, 0.5 mg./kg.	30	63	91
d-Amphetamine sulfate, 0.5 mg./kg. plus 5 mg./kg. of N-(3-dimethylaminopropyl)-2,3-hexamethyleneindole hydrochloride.	30	28	73
Diethylpropion hydrochloride, 2 mg./kg.	19	63	80
Diethylpropion hydrochloride, 2 mg./kg. plus 5 mg./kg. of N-(3-dimethylaminopropyl)-2,3-hexamethyleneindole hydrochloride.	19	40	84

EXAMPLE 3

The absence of any significant appetite inhibiting effect of N-(3-dimethylaminopropyl)-2,3-hexamethyleneindole by itself at a dosage level of 5 mg./kg. was shown by tests on 17 rats, as follows.

It is to be noted that in the 34 comparisons shown in the following table of drug with no drug, only nine cases occur showing less appetite under influence of this drug, and the mean of comparable tests shows slightly increased appetite. Twenty out of the 34 show increased appetite, and 5 show no effect.

Rat No.	15 minute reading (cc. milk)		60 minute reading (cc. milk)	
	No drug (average of 5 readings)	N-(3-dimethylaminopropyl)-2,3-hexamethyleneindole (5 mg./kg.)	No drug (average of 5 readings)	N-(3-dimethylaminopropyl)-2,3-hexamethyleneindole (5 mg./kg.)
1	15.0	17.5	16.6	17.5
2	12.2	13.9	15.7	13.9
3	17.5	16.2	20.6	18.6
4	8.6	12.6	10.2	15.0
5	19.5	16.9	19.5	16.9
6	25.0	25.0	25.0	25.0
7	9.1	9.7	9.8	9.7
8	9.9	11.1	9.9	11.1
9	10.1	18.7	18.0	18.7
10	24.4	25.0	24.9	25.0
11	9.6	13.7	9.8	16.7
12	15.0	16.4	15.0	16.4
13	17.1	21.9	19.8	25.0
14	22.9	17.7	25.0	25.0
15	20.5	17.1	21.6	19.5
16	16.2	13.0	20.0	13.0
17	6.9	8.9	8.7	13.6
Mean	15.3	16.2	17.1	17.7

Although the above examples show the combination treatment with a phenethylamine-type drug and a 2,3-substituted N-(aminoalkyl) indole administered by intra-

peritoneal injections, these drug combinations may be administered orally with comparable results.

In the foregoing general description of my invention there have been described certain alkylaminoalkyl substituted polymethylene indoles represented by generic Formula II as antidepressant components of my novel therapeutic composition. However, certain other known anti-depressant agents which may be generally represented by the formula:

10

15 and acid salts thereof wherein B is selected from radicals of the group consisting of

20 and

and A is selected from the group consisting of

and

30 with R representing hydrogen or methyl, may equivalently be employed as the antidepressant. The following examples will illustrate some of these.

EXAMPLE 7

35 The following example further illustrates some further embodiments of appetite depressant therapeutic compositions within the scope of my invention and the test results obtained from animal evaluation:

40

Drug and Dosage	No. of Rats	Average Milk Intake (percent of no drug control)	
		15 min.	60 min.
A (5.1 mg./kg.)+C	30	28	73
B (5.0 mg./kg.)+C	14	46	90
C (0.5 mg./kg.)	30	63	91

50

A=1-(3-dimethylaminopropyl)-2,3-hexamethyleneindole hydrochloride.

B=5-(3-dimethylaminopropyl)-10,11-dihydro-5H-dibenz[b,f]azepine hydrochloride.

C=d-Amphetamine sulfate.

EXAMPLE 8

55 Other data were obtained from a weight-loss test. Rats are injected with 5 mg./kg. of the test drug, then 20 minutes later with 0.75 mg./kg. of d-methamphetamine hydrochloride. The loss in weight 6 hours after the methamphetamine injection serves as the indicator of activity.

60

Drug and Dosage	No. of Rats	Mean Weight Loss after 6 hrs. (Gm.)
A	10	16.3
B	10	13.0
C	10	13.0
D	10	5.2

65 A=1-(3-dimethylaminopropyl)-2,3-hexamethyleneindole hydrochloride+d-methamphetamine.

B=5-(3-dimethylaminopropyl)-10,11-dihydro-5H-dibenz[b,f]azepine hydrochloride+d-methamphetamine.

C=10-(2-dimethylaminopropyl)phenothiazine+d-methamphetamine.

D=Methamphetamine alone.

70 As a general statement of utility of the products of my invention it may be stated that they are useful in the suppression of appetite in various types of mammal. In this respect it is of course at once obvious that they would be

extremely useful in the field of veterinary medicine where control of appetite is deemed to be desirable. As a still further use, my particular formulations are also of value in pharmacological evaluation of various pharmaceutical agents possessing properties of inhibition of appetite and weight control. From a consideration of the invention as generally described and further particularized by the several illustrative examples set forth, it is to be understood that many other uses will become obvious to those skilled in the art.

What is claimed is:

1. An appetite controlling therapeutic composition which comprises a pharmaceutically effective dose of

(A) a compound of the group consisting of
(1) a phenethylamine of the formula:

5

10

15

20

and

(2) the pharmaceutically-acceptable acid salts thereof; wherein R¹ represents lower alkyl; R² represents a substituent selected from the group consisting of hydrogen and methyl; R³ and R⁴ each represent a substituent selected from the group consisting of hydrogen and lower alkyl of up to six carbon atoms; X represents a substituent selected from the group consisting of hydrogen, halogen and trifluoromethyl; and Y represents a substituent selected from the group consisting of

25

30

35

and

40

wherein Z when alone represents hydrogen, and when concatenated with R⁴ forms therewith a heterocyclic ring of the structure:

wherein n represents an integer from 2 to 3, to result in a compound of the formula:

wherein R¹, R², R³, X and n each has the meaning defined hereinbefore, and

(B) an aminokylpolycyclic compound capable of alleviating depression in mammals and selected from the group consisting of

(1) compounds of the formula:

65

70

and pharmaceutically acceptable salts thereof; wherein W is a member selected from the group consisting of hydrogen, halogen, lower alkyl, nitro, amino, hydroxy and lower alkoxy; R⁵ and R⁶ are each substituents selected from the group consisting of hydrogen and lower alkyl; m is an integer of from 0 to 4; Am is selected from the group consisting of primary, secondary, and tertiary amine groups containing up to eight carbon atoms, and D represents a bivalent organic group selected from the group consisting of:

(a) polymethylene groups containing 5 to 13 carbon atoms, and

(b) aryl of the formula:

(2) compounds having the formula:

and pharmaceutically acceptable acid salts thereof; wherein A is selected from the group consisting of:

wherein R₂ represents a substituent selected from the group consisting of hydrogen and methyl.

2. An appetite controlling therapeutic composition according to claim 1 wherein the phenethylamine is amphetamine.

3. An appetite controlling therapeutic composition according to claim 1 wherein the phenethylamine is mephentermine.

4. An appetite controlling therapeutic composition which comprises a pharmaceutically effective dose of amphetamine and 1-(3-dimethylaminopropyl)-2,3-hexamethyleneindole.

5. An appetite controlling therapeutic composition which comprises a pharmaceutically effective dose of the pharmaceutically acceptable mineral acid salts of amphetamine and 1-(3-dimethylaminopropyl)-2,3-hexamethyleneindole.

6. An appetite controlling therapeutic composition in unit dosage form which comprises 5 to 200 milligrams of a composition comprising amphetamine sulfate and 1-(3-dimethylaminopropyl)-2,3-hexamethyleneindole.
